UNITED STATES PATENT OFFICE.

JAMES A. EVERITT, OF INDIANAPOLIS, INDIANA.

DESIGN FOR A HOPPER FOR SEED-PLANTERS.

SPECIFICATION forming part of Design No. 28,660, dated May 17, 1898.

Application filed November 6, 1897. Serial No. 657,706. Term of patent 7 years.

To all whom it may concern:

Be it known that I, JAMES A. EVERITT, a citizen of the United States, residing at Indianapolis, in the county of Marion and State 5 of Indiana, have invented a certain new Design for a Hopper for Seed-Planters, of which the following is a specification.

Figure 1 is a perspective view of a hopper, showing my new design; and Fig. 2, a vertical section of same on the dotted line 2 2 of Fig. 1.

A represents the front end of the hopper, which occupies an approximately vertical position, and B the opposite or rear end, which 15 is curved at the top and continues thence in an oblique line toward the end A. The outer or near side of the hopper, as shown in the drawings, has a series of slots at its upper portion, forming an open-work, shown as a

series of radial slots C, which will be relieved by the angular projections D.

The lower portion of the hopper side is provided with the ribs E, which radiate from a center approximately at the lower end of the hopper.

Having described my invention, what I claim as new, and wish to secure by Letters Patent, is—

The design for a seed-planter hopper, substantially as described and shown.

In witness whereof I have hereunto set my hand and seal, at Indianapolis, Indiana, this 29th day of October, A. D. 1897.

JAMES A. EVERITT. [L. S.]
